ABSTRACT OF THE DISCLOSURE

This invention teaches the incorporation of non-nesting deformations into a normally nesting sheet metal object to enable such objects to be stacked and unstacked with ease manually or dependably by automatic machinery.

Background of the invention

Sheet metal objects are routinely manufactured by stamping in suitable dies. Such a stamping procedure often involves the preparation and stacking of identical sheets of metal as blanks or the stacking of essentially duplicate parts during some portion of the manufacturing procedure.

Difficulty has been encountered in the past from the tendency of stacked sheet metal blanks or stacked and nested stamped parts to tenaciously cling together and resist separation for subsequent processing particularly if the parts are prepared from oiled stock. This difficulty has resulted in the necessity for the use of more manpower in the attendant sheet separation or in rendering automatic machinery for such stamping processes more expensive and more unreliable than with the current process.

Description of the invention

The difficulties outlined above may be avoided by properly deforming the sheet metal blanks at any suitable step in the manufacturing process. Stamping processes of this nature usually start with the preparation of sheet metal blanks from a metal reservoir normally a coil of sheet metal. Immediately after the blanks have been severed in sequence from the coil, each individual blank should be worked to impart to it at least one local and non-structural deformation. The non-structural deformations in these sheet metal blanks should be located so that it is impossible for such a sheet metal blank to nest with either the sheet metal blank immediately preceding or immediately following such blank.

This invention is easily visualized by a study of the drawing which depicts a pair of stampings which are intended to serve as a portion of an automotive gasoline tank. These two stampings are identical except for the location of the non-structural deformations or "dimples." Note that dimples A and B in the lower stamping are located differently from dimples C and D in the upper stamping. It is obvious that these two stampings may be partially but not completely nested and that when so partially nested they may readily be separated for further

2

processing. This separation may be done either manually or by machine.

It is clear that the dimples or non-structural deformations may be added to the stamping at any convenient point in the process. For example, this dimpling may be done as a portion of the process for the preparation of the blanks or may be done as a part of the stamping or drawing process by which the stampings are fabricated.

It is clear that the non-structural deformations or dimples must be located so that they do not interfere with the utility of the final product or where they may be trimmed away from the final product.

An obvious variation of the process shown above is to modify the structure shown in the drawing so that dimples A and B are coincident with dimples C and D but of different outline so that nesting is again impossible. This structure is shown in the dotted dimples in the upper portion of the drawing with the outline of the dimples D' and C' modified so that nesting with dimples A and B is impossible even though the two sets of dimples are in the same location.

I claim as my invention:

1. The process of producing stampings from flat sheet metal comprising preparing in sequence a plurality of flat sheets of metal of suitable size to be deformed into a stamping, and locally imparting a non-structural deformation to different locations in each of the sheets of metal so produced, these non-structural deformations being located in each individual sheet so that it cannot nest tightly with either the immediately preceding or the immediately following sheet.

2. The process recited in claim 1 in which the non-structural deformations are imparted to the sheets of metal as an adjunct to the preparation of the sheets of metal from a metal reservoir.

3. The process recited in claim 1 in which the non-structural deformations are imparted to the sheets of metal as a portion of the stamping process.

4. The process of producing stampings from flat sheet metal comprising preparing in sequence a plurality of flat sheets of metal of suitable size to be deformed into a stamping, and locally imparting a non-structural deformation to different locations in each of the sheets of metal so produced, these non-structural deformations being arranged in each individual sheet so that it cannot nest tightly with either the immediately preceding or the immediately following sheet.
